US00D823139S

(12) **United States Design Patent** (10) **Patent No.:** **US D823,139 S**
(45) **Date of Patent:** **** Jul. 17, 2018**

(54) **WATCH**

(71) Applicant: **CITIZEN WATCH CO., LTD.**, Tokyo (JP)

(72) Inventor: **Akihiko Kuroda**, Tokorozawa (JP)

(73) Assignee: **CITIZEN WATCH CO., LTD.**, Tokyo (JP)

(**) Term: **15 Years**

(21) Appl. No.: **29/597,478**

(22) Filed: **Mar. 17, 2017**

(30) **Foreign Application Priority Data**

Jan. 27, 2017 (JP) 2017-001476
